MOVABLE DOLL EYES

Mabel Holestine, Kirkwood, Mo.

Application August 29, 1945, Serial No. 613,263

6 Claims. (Cl. 46—168)

1

This invention relates to toys, and more particularly to eyeball simulations and eyeball mountings for dolls and the like.

An important object of the invention is to provide a novel mobile, eyeball simulation and a mounting therefor which will permit rolling of the eyeball simulation in paths longitudinally of the head or body of the object containing it, as well as in paths transversely thereof. Therefore, the simulations, when properly mounted in the head of a doll, for instance, will provide simulated closing of the eyes as well as rolling of the eyes from side to side.

Another important object is to provide an eyeball simulation mounting of simple but sturdy construction for cooperation with an eyeball simulation of novel construction.

Several factors contribute toward the improper and the proper functioning of eyeball simulations for dolls. They must be particularly mobile and their motions not impeded by frictional engagement with the doll head or complicated mountings. They must be light in weight. They must present, in rolling, as natural appearance as possible. That is, their limits of movement, transversely of the head must be limited to the extent the human eye may roll. These factors have been taken into consideration in the novel eyeball simulation and its mounting.

Other objects and advantages of the invention will be apparent during the course of the following detailed description of the invention, taken in connection with the accompanying drawing, forming a part of this invention, and in which drawing:

Figure 1 is a fragmentary vertical section through a vertically-disposed doll head wherein is contained the novel simulated eyeball and mounting, also in section.

Figure 2 is a similar view but with the head inclined, as in a so-called sleeping position.

Figure 3 is an elevation of the new eyeball simulation and mounting with portions of a doll head shown to illustrate positions of parts while the eyeball simulations have reached one limit of rolling.

Figure 4 is a perspective view of the novel eyeball simulation.

Figures 5 and 6 are perspective views of two portions of the mounting therefor.

In the drawing, wherein for the purpose of illustration is shown a preferred embodiment of the invention and wherein similar reference characters throughout the several views, the letter A designates the new eyeball simulation, the

2

letter B the novel mounting associated therewith, C, a weighted actuator for the eyeball simulation A, and D a doll head.

The eyeball simulation A comprises a hollow body portion 10 with the wall thereof curved to represent the front part of a human eyeball, with the outer surface thereof slightly raised as at 11 and carrying an iris 12 and pupil 13. This body portion 10 has an edge 14 providing a major opening 15 and an arcuate opening 16 extending from the edge 14 toward the iris 12 but falling short thereof, as may be seen in Figure 4. The wall of this arcuate opening 16 has, of course, an edge 17. The inner surface of the body portion 10 is designated as 18.

The mounting B includes a substantially semi-spherical hollow member or shell 20, being only partly spherical but greater than a hemisphere, a sphere 21, partly covered by the member 20 and over the surface of which it slides, a mounting or support pin 22 for the sphere and a stop pin 23 projecting from the sphere 21.

The substantially semi-spherical, hollow member 20 is, preferably, smooth-surfaced, especially 25 as for its under or inner surface 24 and is smaller in radius than the body portion 10. By referring to Figure 5, it will be noted that extending from the edge 25 of the member 20 are a plurality of spaced apart cutouts 26, and an arcuate opening 30 27 has an edge 28. The reason for these will be explained in connection with the sphere 21.

This sphere 21 is of a size to mount the member 20 in such a way that the material of the member 20, to either side of the cutouts 26 may 35 be bent, for example, over portions of the surface 29 of the sphere 21 so that the edges 30 of the cutouts will substantially meet, as in Figure 1, for instance, and thus retain the member 20 from dropping from the sphere 21, yet the former may

40 slide over the surface of the sphere. Of course, the member 20 must encompass over half the area of the sphere 21 exclusive of the area thereof not covered because of the arcuate opening 27, so that the member 20 will not become accidentally detached from the sphere 21.

Secured to and extending radially from the sphere 21 is the elongated support pin 22. This may be a fairly stout pin the free end of the shank thereof being adapted to extend into and 45 be anchored in the material of the doll head D. This pin 22 provides more than a support, as will be subsequently explained.

The stop pin 23 is, preferably, a short one, extending radially from the sphere 21 and with the axes of the two pins forming substantially a

right angle. Its function will be explained, after a description of the actuator C.

This actuator C for the eyeball simulation A, includes a, preferably, arcuate arm 35, terminating at its free end 36 in a depending weight 37 and with its other end 38 embedded in a body 39 of suitable material which has the dual function of fixedly connecting the hollow body portion 10 and semi-spherical hollow member 20, and retaining them spaced apart, as in Figures 1 and 2, with the longitudinal axes of the arcuate openings 16 and 27 intersecting. That is, the axis of the opening 27 intersects the axis of the opening 16 within the limits of the opening 16.

The length of the stop pin 23 extending from the sphere 21 is insufficient to contact the inner surface 18 of the body portion 10, but will contact the edge 28 of the arcuate opening 27. Thus the pin 23 limits movement of the member 20 with respect to the sphere 21. An example of this may be seen in Figure 3.

It is also obvious, as in Figure 1, that the support pin 22 prevents the weight 37, being acted upon by gravity, from drawing the eyeball simulation around so that the iris 12 and pupil 13 would disappear in an upward direction, and it will be noted, as in Figure 2, that the support pin 22 has also the function of limiting movement of the member 10 with respect to the sphere 21, since the edge 17 of the opening 16 contacts the shank 22 at times (when the head D is in a horizontal or nearly horizontal position) and the pin 23 is prevented from leaving the arcuate opening 27.

The eyeball simulation A and mounting B, with the actuator C, may be marketed as a unit. Either one of two methods of assembly is possible. The portion 10, member 20, with the cutouts 26 open, as in Figure 5, and actuator C are secured together by the body 39, which may be solder, cement, a modern plastic material or any other suitable material having adhesive and hardening characteristics. This assembly may then be mounted upon the sphere 21 carrying the pins 22 and 23 and the material of the member 20, between the cutouts 26 bent over the sphere 21 as in Figures 1 and 2, thus securing the assembly A and C to the mounting B, but so that there may be movement of the member 20 over the sphere 21 or the member 20 may first be movably secured to the sphere 21 and then the other portions mounted upon the member 20.

The doll head D may be of any suitable hardened plastic material and the free end of the pin 22 inserted into the body 40 of this material below the eye openings 41 in the head, these openings being shaped to conform to the eyeball simulation.

Normally when the head D is at rest and disposed as in Figure 1, the pupil 13 and iris 12 of each eyeball simulation A will occupy substantially the center of each opening 41, and the axes of the pins 22 and 23 will intersect the longitudinal axes of the arcuate openings 16 and 27 respectively. However, when the head D is tipped, as in Figure 2 gravity will cause the eyeball simulation A to move so that the iris 12 and pupil 13 will disappear and there will be the appearance of closed eyes. Should the head be rolled from side to side, while the same is in the position shown in Figure 2, the eyeball simulation A will not move, as may be appreciated from the positions of the pins 22 and 23 at the extreme inner ends of their respective arcuate openings. On the other hand, when the head is in the

position shown in Figure 1, when the head is rolled from side to side the pins do not impede moderate rolling of the eyeball simulation, but excessive rolling of the eyeball simulation is prevented (since the pins contact the edges of their respective arcuate openings).

From the foregoing, it will be seen that a simple, economical assembly of eyeball simulation and mounting therefor is provided, wherein there is no complicated attachment of mounting to doll head, nor eyeball simulation to mounting. Yet a very lifelike rolling of the doll eyes is possible, as well as disappearance of the iris and pupil, simulating closed eyes.

Various changes may be made to the form of the invention herein shown and described without departing from the spirit of the invention or scope of the claims.

What is claimed is:

1. In a rolling doll eye assembly, a hollow, mobile, eyeball simulation, provided with a major opening and a minor arcuate opening extending to the major opening and toward the iris of the eye; a weighted arm; a hollow, semi-cylindrical member with the major portion thereof disposed within said hollow eyeball simulation and spaced therefrom, said member having a major opening facing said arcuate opening, and an arcuate opening extending from said last-named major opening and facing the interior surface of said hollow eyeball simulation; means connecting said eyeball simulation, semi-spherical member and said weighted arm, with the weight thereof depending, and the arm thereof extending outwardly and downwardly from the rear portion of said eye assembly; a sphere with the major portion thereof disposed within said hollow, semi-spherical member; a stop pin mounted upon said sphere and disposed within the second-named arcuate opening; and a support pin extending from the sphere and disposed within the paths of travel of the walls of said first-named arcuate opening and the edge of said semi-spherical member.

2. In a rolling doll eye assembly, a hollow, mobile, eyeball simulation, provided with a major opening and a minor arcuate opening extending to the major opening and toward the iris of the eye; a weighted arm; a hollow, semi-cylindrical member with the major portion thereof disposed within said hollow eyeball simulation and spaced therefrom, said member having a major opening facing said arcuate opening, and an arcuate opening extending from said last-named major opening and facing the interior surface of said hollow eyeball simulation; means connecting said eyeball simulation, semi-spherical member and said weighted arm, with the weight thereof depending, and the arm thereof extending outwardly and downwardly from the rear portion of said eye assembly; a sphere with the major portion thereof disposed within said hollow, semi-spherical member; a stop pin mounted upon said sphere and disposed within the second-named arcuate opening, extending radially toward and falling short of said eyeball simulation; and a support pin extending from the sphere and disposed within the paths of travel of the walls of said first-named arcuate opening and the edge of said semi-spherical member.

3. In a rolling doll eye assembly, a hollow, mobile, eyeball simulation, provided with a major opening and a minor arcuate opening extending to the major opening and toward the iris of the

eye; a weighted arm; a hollow, semi-cylindrical member with the major portion thereof disposed within said hollow eyeball simulation and spaced therefrom, said member having a major opening facing said arcuate opening, and an arcuate opening extending from said last-named major opening and facing the interior surface of said hollow eyeball simulation; means connecting said eyeball simulation, semi-spherical member and said weighted arm, with the weight thereof depending, and the arm thereof extending outwardly and downwardly from the rear portion of said eye assembly; a sphere with the major portion thereof disposed within said hollow, semi-spherical member; a stop pin mounted upon said sphere and disposed within the second named arcuate opening; extending radially toward and falling short of said eyeball simulation; and a support pin extending from the sphere and disposed within the paths of travel of the walls of said first-named arcuate opening and the edge of said semi-spherical member, the axes of said pins forming substantially a right angle.

4. In a rolling doll eye assembly, a hollow, mobile, eyeball simulation, provided with a major opening and a minor arcuate opening extending to the major opening and toward the iris of the eye; a weighted arm; a hollow, semi-cylindrical member with the major portion thereof disposed within said hollow eyeball simulation and spaced therefrom, said member having a major opening facing said arcuate opening, and an arcuate opening extending from said last-named major opening and facing the interior surface of said hollow eyeball simulation; means connecting said eyeball simulation, semi-spherical member and said weighted arm, with the weight thereof depending, and the arm thereof extending outwardly and downwardly from the rear portion of said eye assembly, comprising a body portion extending from said eyeball simulation and semi-spherical member at the edge portion of said eyeball simulation and at the portion of said semi-spherical member opposite said second named arcuate opening; a sphere with the major portion thereof disposed within said hollow, semi-spherical member; a stop pin mounted upon said sphere and disposed within the second-named arcuate opening; and a support pin extending from the

sphere and disposed within the paths of travel of the walls of said first-named arcuate opening and the edge of said semi-spherical member.

5. In a rolling doll eye assembly, a hollow, mobile, eyeball simulation, provided with a major opening and a minor arcuate opening extending to the major opening and toward the iris of the eye; a weighted arm; a hollow, semi-cylindrical member with the major portion thereof disposed within said hollow eyeball simulation and spaced therefrom, said member having a major opening facing said arcuate opening, and an arcuate opening extending from said last-named major opening and facing the interior surface of said hollow eyeball simulation; the longitudinal axes of said arcuate openings intersecting each other and forming substantially a right angle; means connecting said eyeball simulation, semi-spherical member and said weighted arm, with the weight thereof depending, and the arm thereof extending outwardly and downwardly from the rear portion of said eye assembly; a sphere with the major portion thereof disposed within said hollow, semi-spherical member; a stop pin mounted upon said sphere and disposed within the second-named arcuate opening; and a support pin extending from the sphere and disposed within the paths of travel of the walls of said first-named arcuate opening and the edge of said semi-spherical member.

6. A mounting for an eyeball simulation for the hollow heads of figures, said mounting comprising a substantially spherical body; an elongated pin extending radially therefrom; a second pin extending radially therefrom, and a semi-spherical, movable shell extending over a portion of said sphere greater than one-half the area thereof, in face to face contact, said shell having an edge and an arcuate opening extending from said edge, said elongated pin being disposed in the path of movement of said edge of said shell, and said second pin being disposed in said arcuate opening, the position of said elongated pin being such that said edge will contact said elongated pin and prevent movement of said shell to a position wherein said second pin is outside said arcuate opening.

MABEL HOESTINE.
